United States Patent Office

Des. 223,640
Patented May 16, 1972

223,640

LETTER HOLDER
Margaret J. Kemp, 6006 Baudry, Houston, Tex. 77035

Filed Feb. 26, 1971, Ser. No. 119,438

Term of patent 14 years

Int. Cl. D19—099

U.S. Cl. D74—2

FIG. 1

FIG. 2

FIG. 3

FIG. 4

FIG. 1 is a perspective view of the letter holder constructed in accordance with my design;

FIG. 2 is a side elevational view of the letter holder shown in FIG. 1;

FIG. 3 is a front elevational view of the letter holder shown in FIG. 1; and

FIG. 4 is a rear elevational view of the letter holder illustrated in FIG. 1.

I claim:

The ornamental design for a letter holder, as shown.
